(57) **CLAIM**

We claim, the ornamental design for a capacitor busbar device, as shown and described.

DESCRIPTION

FIG. 1 is a front top perspective view of a capacitor busbar device showing our new design;

FIG. 2 is a top view thereof;

FIG. 3 is a bottom view thereof;

FIG. 4 is a first side perspective view thereof;

FIG. 5 is a second side perspective view thereof;

FIG. 6 is a front perspective view thereof; and,

FIG. 7 is a rear perspective view thereof.

The broken lines depict portions of the capacitor busbar device that form no part of the claimed design.
